HEINRICH TOUSSAINT, OF KIEL, AND HUGO FLUCK, OF HAMBURG, GERMANY, AS
SIGNORS TO DEUTSCHE WERKE AKTIENGESELLSCHAFT, OF BERLIN, GERMANY, A
CORPORATION OF GERMANY.

DREDGING BUCKET.

Application filed September 19, 1922. Serial No. 589,090.

To all whom it may concern:

Be it known that we, HEINRICH TOUSSAINT and HUGO FLUCK, both citizens of the German Republic, residing at Kiel and Hamburg, Germany, respectively, have invented new and useful Improvements Relating to Dredging Buckets, of which the following is a specification.

This invention relates to improvements in connection with that type of dredging bucket which is provided with a pivoted guide arm.

Ordinary dredging buckets pivoted by an inclined rear wall to the guide arm and tilted by a rope attached to the bucket have the objection of opening unintentionally when the bucket is in its lowermost position so that thereby dredging capacity is reduced, while in the uppermost position of the bucket the inclined bottom of same hinders the discharging operation. A further objection is that but little mechanical power exists for keeping the bucket closed seeing that this is effected almost alone by the weight of the flap of the bucket.

According to this invention the aforesaid objections are avoided by hinging the bucket to the rear or outside of its rear wall which is integral with or rigidly fixed to the guide-arm, and by attaching the lifting cable above the guide-arm to an extended lug rearward of the hinge-pin of the bucket. With the parts disposed in this manner, it will be noticed that the suspending moment and the force applied for opening the bucket produce turning moments in opposite directions, while the closing of the bucket is effected by the pull of the lifting cable in a very reliable manner.

The accompanying drawings show an embodiment of the invention.

Figures 1 to 4 are side views showing different positions of the bucket; and Fig. 5 is a side elevation of a dredger provided with the improved bucket arrangement.

The guide-arm S is rigidly connected to the rear wall R of the bucket. On the outside of the rear wall is the hinge-joint B on which the movable body of the bucket turns. The movable part of the body of the bucket has its point of suspension A at the rear of its hinge-joint B, the suspension being formed by the attachment of the cable

H. On the body L of the bucket in the forward direction of the hinge-joint B is the point C for the attachment of the relief cable O, while the cable H gives the pull for the dredging operation and for keeping the bucket closed. For opening the bucket it is necessary to pull the cable O and then hold it fast, whilst releasing the cable H.

As will be seen at Fig. 5 the relieving cable O is wound on the drum T, while the suspension cable is wound on the drum F. In coupling together these two drums and rotating same at equal speeds, the bucket L will be raised or lowered without causing relative movement between the body L and the rear wall R of the bucket. In disengaging the drum-coupling or clutch, the two cables can make a relative movement for opening or for closing the bucket.

Fig. 1 shows the bucket in its lowermost position at the beginning of the dredging operation, when the resistance to the digging-edge D, the weight G of bucket L and the pull of the cable H produce turning moments in clockwise direction composed as follows: D_{ab} ; G_{as} ; H_{xa} ; which close the bucket.

Fig. 2 shows the bucket filled as it emerges from the dredging operation. Here, as in Fig. 1, the digging edge and weight of bucket and its charge produce clockwise directed moments and keep the bucket closed. Any tendency by the weight of the charge to force the bucket L away from its rear wall R is strongly opposed by the clockwise directed turning moment of the lifting cable H, being: H_{za} . The more heavy may be the dredging charge, the stronger will be the pull of the lifting cable and the result is greater closing power.

Fig. 3 shows the bucket in its middle position opened by the relief of the pull from the lifting cable H and the suspension of the bucket at C. The opening of the bucket may also be effected by a direct pull of the cable O. In both cases it is quite easy to obtain a quick or a slow or a partial opening and closing of the bucket.

Fig. 4 shows the bucket in its most elevated discharging position. In this position also the facility for opening and closing the bucket are the same as explained

with reference to Fig. 3. The emptying of the bucket occurs in a reliable manner, because the inclined rear wall R assumes not nearly the angle where sliding stops, so that even sticky material can slip off.

In placing the point A rearward of the hinge-joint, the pull of the lifting cable H, the weight of the bucket with its charge and the digging effort together produce a closing action. In disposing the relieving cable O, forward of the hinge joint B, at the point C the time for opening and closing and the extent of opening can be readily regulated. By slackening the cable H at its point of attachment A it is also possible to open the bucket without pulling the cable,

in allowing the weight of the guide-arm and rear wall to come into effect.

We claim:

The combination with a guide-arm having 20 a rigidly fixed rear-wall and a lug projecting at right angles from the arm and the said wall, of a dredger bucket, a hinge-joint for the bucket on said lug, extensions of the sides of the bucket rearward of its hinge-joint, a lifting cable fast to said extensions rearward of the hinge-joint, and a relief cable attached to the bucket in a forward 25 point of the hinge-joint, as and for the purpose stated.

HEINRICH TOUSSAINT.
HUGO FLUCK.
